MOULDING STRIP

Frank P. Uphues, Chicago, Ill., assignor to Crane Co., Chicago, Ill., a corporation of Illinois

Application January 21, 1952, Serial No. 267,485

6 Claims. (Cl. 4—187)

This invention relates generally to a moulding strip, and, more particularly, it is concerned with a novel type of filler strip for use with sinks associated with countertops, lavatories, and the like, in which a sanitary connection is made between the sink and lavatory fitted with the countertop or adjoining cabinet or table.

Heretofore, with a sink of the type illustrated hereafter and described, it has been necessary to use an extended moulding strip and more frequently having it preferably cut out by hand in order to fit the relatively unsymmetrical or irregular contour forming a corner at the back of the sink. Needless to say, this has been costly and also in many instances did not develop too accurately as a solution.

Therefore, it is one of the more important objects of this invention to provide a better and more simple and inexpensive method of making this type of joint between the countertop of the sink or lavatory as well as improving the appearance and simplifying the installation itself by means of employing a cornerpiece casting.

Another object is to provide for a moulding strip in which the points of contact in back of the sink are in such a position that they are on areas where a curve with a single radius constitutes the point of contact rather than areas having a curve with the compound radii heretofore employed which not only provides a better contact curve with the sink back, but it simplifies the installation very substantially and reduces the amount of special fitting time and labor involved in making the final assembly.

Another object is to provide a corner casting or other suitably formed member serving as a fillet for the corner joint between the sink or the lavatory and the table or countertop, making it easier to keep the assembly clean and neat and also provide an improved overall appearance.

Other objects and advantages will become more readily apparent upon proceeding with the following description read in light of the accompanying drawings, in which

Fig. 1 is a fragmentary exterior view showing a conventional application of my invention.

Fig. 2 is a front view of the novel corner mounting strip constituting my invention.

Fig. 3 is a plan view thereof.

Fig. 4 is a bottom view of the article embodying the invention.

Fig. 5 is a side view looking at the structure towards the sinkback.

Fig. 6 is a side view viewing the structure in the direction toward the countertop.

Similar reference numerals refer to similar parts throughout the several views.

Referring now to Fig. 1, a conventional sink, generally designated 1, is fragmentarily shown having the usual back portion 2, the end limits of which are normally rounded as indicated and extends downwardly vertically shown to form the drainboard portion of the sink. In the modern kitchen usually extending in close association therewith is a countertop 3 provided with the usual end

2

or backrail strip 4. Obviously, if the sink or the countertop were ordinarily left spaced-apart slightly, it could easily become the source of considerable objection in the manner of establishing and maintaining an unsanitary condition because of food particles and the like falling and lodging therebetween. Thus, it has been found that if a simple corner member, generally designated 5, is used and is further supplemented by means of an elongated T cross section filling strip portion, generally designated 6, either integral or in abutting relation therewith, a neat and sanitary connection may be made between the sink back board and drainboard portion and the countertop.

However, it is, of course, desirable from the expense viewpoint to avoid costly constructions requiring special treatment in a custom built or hand-made manner and specifically avoiding the compound radii curves heretofore used for example in order to fit snugly with both the vertical surface 7 and the curved and filleted surfaces at 8 and 9 respectively of the sink or lavatory. It has been discovered, as more clearly shown in Fig. 3, that the curvature of the corner piece required to fit the sink surfaces 7 and 8, and designated 11 and 12 respectively on the corner piece 5 is very simply provided because it merely entails forming a curved edge terminating at the surface 13. Generally, it has been found that in order to meet the curvature of the sink surface at 9 this is easily done as more clearly shown in Figs. 5 and 6 by forming the curved edge 14 in a single plane to match with the curved surface or fillet 9 of the sink 1. Thus, the filler piece curvature for the rounded and narrow edge 8 of the sink extends in one plane defined by the narrow horizontal edge 12, while the curved portion 14 of the mounting for the sink fillet 9 extends in a vertical plane transverse to the rounded edge 12 and thus is similarly formed easily. The numeral 15 designates the end limit transverse surface of the filler member mounting, abutting the straight molding strip 6. It has been found preferable in such instances to provide the slightly raised edges on each side as at 16 for the actual contact surfaces with the sink or lavatory. It has also been found desirable for more secure positioning to have a lower depending central web portion 17. For purpose of attachment to the countertop or the like, it is preferable to provide the screw holes 18 and the mounting strip may be suitably recessed as at 19 to receive the rear raised edge portion 4 of the countertop 3.

At 10, the letter L is provided to indicate that the corner filler strip mounting 5 is intended for use on the left side of the sink, while the letter R obviously may be used to designate a right-hand mounting relative to the sink.

It will be clear from the constructions illustrated and described that a relatively simple radius or curve can easily be provided at the line of the contact of the filler strip with the sink and a plain edge contact as at 16 is provided at the countertop juncture and eliminating thereby the accumulation of food crumbs or other matter tending otherwise to cause an unsanitary condition to exist. At the same time, by making the elongated strip member 6 of an independent structure, it enables the assembled mounting to be more flexible and more easily adjustable with respect to the countertop and sink width.

While only a single embodiment has been shown, it should, of course, be clear that this is for purpose of illustration only and therefore that the scope of the invention should be measured by the appended claims.

I claim:

1. The combination of a moulding and sink, comprising a fillet member mounting strip for installation between the end portion of a back of a sink and of an adjoining countertop when the latter members are disposed in slightly spaced-apart end relation, the combina-

tion including a sink having a back rounded end portion adjoining the countertop, the said mounting strip being fitted therebetween and consisting of a corner member having a recessed portion defined by an outer curved surface extending upwardly to form substantially a right angle, the surface of the latter portion being defined by a curved edge following the contour rounded portion of the back of the sink, the curved edge thereof having a vertically extending curved portion of substantially 90 degrees and being limited by an end transverse surface extending in a vertical plane commencing substantially at the point of tangency with the latter curved portion with its end limits defined by a plain edge transverse surface.

2. The combination of a moulding and sink, comprising a fillet member mounting strip for installation between the corner and back portion of a sink and of an adjoining countertop having a rear raised end portion when the latter members are disposed in slightly spaced-apart end relation, the combination including a back rounded end portion adjoining the countertop the said mounting strip being fitted therebetween and consisting of a corner member having a recessed portion defined by an outer curved surface extending to form a right angle portion thereof, the surface of the curved portion being defined by a curved portion following the contour of the back round end portion of the sink, the curved edge thereof being defined by a vertically extending curved surface of substantially 90 degrees, the latter curve being limited by transverse surface in a vertical plane extending substantially to the point of tangency with the latter curved portion, and having one of its outer end limits defined by a plain edge surface extending in a horizontal plane, the said latter edge surface being interrupted at the other limit by a recessed portion for receiving the said rear raised end of the countertop.

3. The combination of a moulding and sink, a fillet member mounting strip for installation between the filleted back portion of a sink or the like and of an adjoining countertop when the latter members are in slightly spaced-apart end to end relation, the said mounting strip being on a filleted portion of the sink and consisting of a corner member having an outer curved surface extending in a vertical plane limited by a transverse surface constituting a right angle end portion thereof, the under surface of the curved portion being at right angles to said transverse surface and following the contour of the filleted back portion of the sink, the curved edge thereof extending for a range of substantially 90 degrees, the latter curve being limited by a transverse curved surface in a horizontal plane substantially starting at the point of tangency therewith, the latter curved portion having one of its end limits defined by a transverse surface extending in a vertical plane, the said latter transverse surface being defined at one limit by an end portion marking the rear end limits of the countertop.

4. The combination of a moulding and sink, a fillet member mounting strip for installation between the corner and rounded back of a sink and of an adjoining countertop disposed in slightly spaced-apart end relation, the said mounting strip on the rounded back of the sink consisting of a hollow corner member having an outer curved surface extending to form a surface right angle surface por-

tion thereof, the surface of the latter portion being defined by a combined plain and curved edge substantially following the contour of the rounded back of the sink, the latter curved edge thereof being vertically extending and with the curved portion extending through a range of substantially 90 degrees and with the latter curved portion being limited by transverse surface extending in a horizontal plane starting substantially at the point of tangency with the latter curved portion having one of its end limits defined by a transverse surface extending in a vertical plane, the said plain edge surface being interrupted at one limit by a curved recessed edge portion extending in a horizontal plane.

5. In a combination of a moulding and sink, a fillet member mounting strip for installation between the back corner portion of a sink and of an adjoining countertop or the like in slightly spaced-apart end-to-end relation, the combination of a sink and countertop the said mounting strip consisting of a corner member supported on said sink and countertop and having an outer curved vertical surface extending to form a right angle end portion thereof, the surface of the curved portion being supplemented by a straight portion following the contour of an end limit of the back of the sink in a horizontal plane, one of the curved edges thereof being defined by a vertically extending portion of substantially 90 degrees range, the latter curved portion being limited by transverse curved surface extending in a vertical plane substantially starting at the point of tangency with the curved portion and having one of its end limits defined by a transverse rear edge, the said latter edge also defining the rear end limits of a plain straight edge of said corner member extending from the forward portion of the sink and countertop.

35. 6. In a combination of a moulding and sink, a fillet member mounting strip for installation between the back of a sink or the like and of an adjoining countertop in slightly spaced-apart end-to-end relation, the combination of a sink and countertop the said mounting strip including a corner member on the said sink and countertop and having an outer curved surface extending to form a right angle portion thereof, one of the surfaces of the curved portion being defined by a combined curve and straight portion following the contour of the back end limit of the sink, the curved edge forward limits thereof being defined by a vertically extending curved portion of substantially 90 degrees, the latter curve being limited by transverse surface in a vertical plane substantially at the point of tangency with the latter curved portion and having its forward end limit defined by a transverse vertical surface, the said corner member having an oppositely disposed lower straight edge for abutting contact with an upper surface of the countertop, the said transverse vertical surface defining the forward limits of the said lower straight edge.
